PUMP

Charles Tweedie, Jefferson City, Mo.

Application January 30, 1935, Serial No. 4,021

2 Claims. (Cl. 36—57)

My invention relates to pumps of the kind that are made by stitching the lining to the upper along the top edge of the upper and afterward cutting the lining just above the stitching. Pumps of this type have many favorable points but they have one shortcoming, namely, that, in the movement of the foot within the shoe, the raw edge of the lining at the front of the opening is liable to chafe the foot and cause considerable discomfort.

The principal object of the present invention is to overcome this objection without sacrificing the favorable points of the old pump. The invention consists principally in the method hereinafter described of incorporating an edge protecting strip at the front of the foot opening in the course of manufacturing the pump. It also consists in the pump hereinafter described and claimed.

20 In the accompanying drawing, which forms part of this specification, and wherein like reference numerals refer to like parts wherever they occur,

Fig. 1 is a view of a pump embodying my invention,

Fig. 2 is a detail view showing the form of the protective strip,

Fig. 3 is a view of the topside of the upper with the lining and protective strip stitched thereto prior to the folding of said strip,

Fig. 4 is a cross-section on the line 4—4 of Fig. 3,

Fig. 5 is a top view of the upper after the edge of the lining is trimmed and the protective strip is folded back along the line of stitching and is secured to the underside of the lining,

Fig. 6 is a cross-section on the line 6—6 of Fig. 5,

Fig. 7 is a view of an upper from the inside illustrating the lining pattern and stitching commonly used heretofore when the lining is made with the quarters separate from the vamp, and

Fig. 8 is a similar view showing the patterns of the vamp and quarter linings changed conformably to my invention.

My pump comprises an upper 1 and a lining 2 therefor stitched together close to the top edge of the upper. At the front of the foot opening of my pump is a protective strip 3 with a narrow portion exposed on the upper face of the upper and with a wider portion doubled back onto the lining. Preferably this protective strip is of the same material as the upper and arranged to appear as a part thereof. For this

purpose, the protective strip is stitched to the upper and then doubled back first along the line of stitching 4 and then again doubled back over the edge of the upper, the inturned portion being preferably secured flatwise to the lining by suitable cement 5.

In manufacturing my pump, I follow ordinary practice except in the particulars hereinafter noted. In ordinary practice, the lining and the upper are top stitched together by a line of stitching 4 close to the top edge of the upper, after which the margin of the lining is cut off along the top edge of the upper, whereupon they are ready for assembling and lasting.

According to my method, the protective strip is sewed to the upper 1 by the same line of stitching 4 that secures the lining 2 thereto. Accordingly, the lining and the upper are laid together flatwise as heretofore and the protective strip, preferably of the same material as the upper, is placed on the top of the upper with its grain side facing the grain side of the upper. Then these three parts, namely, the protective strip, upper and lining, are stitched together by the same line of stitching and in the same way as has previously been done without such strip. When the protective strip is sewed to the upper, the margin of the lining is cut off as heretofore. Then the reinforcing strip is folded back along the line of stitching and is again folded back over the edges of the upper and of the lining, and the inturned margin of said protecting strip is cemented or otherwise suitably secured flatwise to the lining. As soon as the cement 5 is dry, the work is ready for assembling, lasting and numerous other manufacturing operations in the ordinary way.

Fig. 2 illustrates a suitable shape for the protective strip in its flat condition prior to stitching. It is noted that one side of the strip is concave and of a length substantially equal to the length of the curve at the front end of the foot opening of the pump, but in the flat condition of the strip the ends of the concave diverge somewhat more than the curve of the shoe opening. This difference represents an allowance that is made so that the ends of the concave may be sprung towards each other in the course of stitching and thereby contribute to the fitting of the strip flatwise against the lining when the strip is folded back.

As my protective strip is of short length and is applied to the upper prior to the lasting, it does not affect the dimensions that are essential to proper fitting of the foot and adds very little

to the cost of manufacture. On the other hand, it is inconspicuous, covers the raw edge of the lining and affords a smooth surface for the foot to bear against.

- 5 I have described my invention as applied to a full vamp pump. It is equally applicable to pumps wherein the quarters are made separate from the vamp and has special advantages with this type of pump. As illustrated in Fig. 7, it is 10 the common practice to make pumps of this type by sewing the front ends of the quarters to the rear end of the vamp by lines of stitches 8 that extend from the shank portion close to the ends of the curve at the front end of the foot opening. It is also the common practice to cut the 15 linings 12a of the quarters with curved extensions 7 at their front ends that meet at the middle of the front curve of the foot opening and are secured together by a short line of 20 stitches 9 extending longitudinally of the shoe at this point. The vamp lining 12b is cut with its rear end conforming to the front ends of the quarter linings with an overlap sufficient for stitching as shown at 6.
- 25 I have described my invention as applied to a full vamp pump but it is applicable to pumps of other designs. It is especially advantageous in connection with pumps wherein the lining is made in sections because it makes it practicable 30 to eliminate a very objectionable seam hump which is formed at the front of the foot opening of the old construction illustrated in Fig. 7. With such old construction, the lining was commonly made in sections with the top portions of 35 the quarter sections extended forwardly, as at 7, and stitched together with a closed seam 9 extending longitudinally of the shoe at the middle of the front end of the shoe opening and also stitched along their overlapping margins by a 40 seam 6 extending from shank to shank. Such lining was then topstitched to the upper. Thus the materials were piled up into a hump at the very place where it is most objectionable.

According to my invention as illustrated in 45 Fig. 8, the quarter lining sections 2a are made without the top extensions 7 above mentioned and the concave middle portion of the vamp lining section 2b is extended rearwardly to make up for such omission. By this arrangement, the

quarter and vamp sections 2a, 2b of the lining are stitched together by seams 10 which extend from each side of the shank to the near end of the curve of the foot opening or thereabout, the 5 vamp lining section extends continuously along such curve and the longitudinal seam 9 and resulting hump of the old construction are eliminated. The protective strip is applied to my sectional lining in the same manner as hereinbefore set forth.

10 It is more or less customary to use leather for lining quarters and drills or the like for lining vamps, the leather being considerably more expensive. As my invention dispenses with the top extensions of the quarter linings and permits the use of smaller pieces of leather, it accomplishes a considerable economy because less of the expensive leather is required and because the additional material of the vamp lining is 15 located at the rear concavity thereof and was 20 wasted under the old practice.

25 Referring to Fig. 7, the saving in leather and the extension of the drill is represented by the space between the line of stitching 6 and the dotted line 8 which corresponds to the line of stitching 10 in the new construction illustrated in Fig. 8.

What I claim is:

1. A pump having at the front of the top edge thereof a short protective strip, said protective 30 strip being a normally flat piece with a concave strip being secured by the top stitching of the pump and being folded over said top edge and secured flatwise to the lining, the stitched edge of said strip being of substantially the same length and 35 curvature as the curve at the front end of the foot opening.

2. A top-stitched pump having a short protective strip at the front of the top edge thereof, said protective strip being a normally flat piece 40 of the same material as the upper and having one edge concave and secured to the upper by the top stitching of the pump, said strip being folded over said top edge and connected to the lining, the stitched edge of said strip being of substantially the same length and curvature as the curve 45 at the front end of the foot opening.

CHARLES TWEEDIE.
